FLOWER HOLDER FOR USE WITH A CANDLE

Walter A. Saxe, Albany, N.Y., assignor to Saxe Brothers, Inc., Albany, N.Y., a corporation of New York

Filed Apr. 20, 1959, Ser. No. 55,567

Term of patent 14 years

(Cl. D35—3)

Fig. 1

Fig. 3

Fig. 2
+ 4

Fig. 4

Fig. 5

FIG. 1 is a top plan view of a flower holder for use with a candle;

FIG. 2 is a front elevational view thereof;

FIG. 3 is a rear elevational view thereof on a reduced scale, the broken line representation of a candle and a candle stick being for illustrative purposes only;

FIG. 4 is a vertical cross-sectional view thereof taken on line 4—4 of FIG. 2; and

FIG. 5 is a bottom plan view thereof.

I claim:

The ornamental design for a flower holder for use with a candle, as shown and described.
